FOLDING GOLF CLUB AND BALL CARRIER

Glenn C. Wright, Cato, N. Y.

Application August 4, 1950, Serial No. 177,601

1 Claim. (Cl. 280—42)

1

The present invention relates to improvements in golf club carriers, for use while playing golf.

An object of the present invention is to provide a novel folding golf club device whereby a set of golf clubs including woods and irons may be desirably positioned on a wheeled carrier for movement over a golf links.

A further object of the present invention resides in the provision of a leg means for the carrier whereby when it is desired to leave the golf club carrier in standing position, the leg is adapted to engage the ground.

A further object of the present invention resides in the provision of a linkage means whereby the ball carrier may be folded for storage purposes and wherein the carrier may be unfolded and rigidly held in unfolded position for use on the golf links.

Still another object of the present invention is to provide a novel arrangement of bracket means for clampingly holding golf clubs whereby the desired club may be readily selected from the group.

The invention also comprises novel details of construction and novel combinations and arrangements of parts which will more fully appear in the course of the following description. However, the drawings merely show and the following description merely describes an embodiment of the present invention which is given by way of illustration or example only.

In the drawings:

Figure 1 is a vertical longitudinal sectional view taken substantially along the plane of line 1—1 of Figure 2 and showing the folding golf club carrier of the present invention;

Figure 2 is a top plan view of Figure 1;

Figure 3 is a view of the folding golf club carrier in folded position;

Figure 4 is a vertical transverse sectional view taken substantially along the plane of the line 4—4 of Figure 1; and

Figure 5 is a vertical transverse sectional view taken substantially along the plane of the line 5—5 of Figure 1.

Referring more particularly to the drawings, wherein like numerals designate like parts throughout, the numeral 10 designates generally the framework of the folding carrier while the numeral 12 designates generally the golf club bracket means, the numeral 14 designating generally the leg supporting means for use in conjunction with the golf club carrier.

The frame 10 of the golf club carrier of the present invention includes a handle bar 16 which

2

is of elongated tubular form having an angulated end 18 upon which a conventional handle 19 is securely positioned for manipulating the carrier. The end of the handle bar 16 opposite to the handle 19 is angulated upwardly at 20 and has secured thereto a cross bar 22 by means of a pin 24. The handle bar 16 is also provided with an axially extending portion 26 which is pivotally connected to the pivot bracket 28 at its extremity.

10 A sleeve 30 is slidably mounted on the handle bar 16 and is provided with thumb screw means 32 whereby the sleeve may be selectively positioned along the length of the handle bar 16. A pair of outstanding hinge brackets 34 are integrally formed with the sleeve 30, and a pair of wheel supporting bars 36 are hingedly connected to the brackets 34 by means of pins 38. The wheel supporting bars 36 terminate in angulated ends 40 which provide wheel supporting bearings 20 and linkage connecting means 42. A pair of wheels 44 are secured on the bearing surfaces by means of the wheel nuts 46. Balloon tires are shown and are preferably used.

25 The linkage means connecting the wheel supporting bars 36 includes two sets of flat straps 48 and 50 which are pivotally connected at their extremities to the linkage connecting means 42 and to the pivot bracket 28 by means of the pins 52.

30 From the foregoing, it will readily be seen that when the carrier is to be folded, the thumb screw 32 is loosened and the sleeve 30 is moved upwardly on the handle bar 16 causing the linkage means to pivot to the position shown in Figure 3 moving the wheels 44 inwardly.

35 The golf club supporting means 12 includes a golf club supporting plate 54 which is provided with an opening 56 through which the heads of the irons may extend. The plate 54 is also provided with a pair of shank supporting bars 58 and 60 for supporting the shanks of the irons and woods respectively. Also positioned on the plate 54 are a plurality of resilient clips 62 which may be provided with felt or the like and which 40 are adapted to clampingly receive the golf clubs for support thereby. The front end of the plate 54 is provided with a bumper guide 64 which is secured to the plate 54 by means of the pins 66, the heads of the woods being adapted to be received in the opening provided thereby as shown 45 best in Figure 1.

50 Intermediate the length of the handle bar 16 is provided the second golf club supporting bracket 68, which is best shown in Figure 5. The bracket 68 is formed from an elongated flat strap

having a clamp portion 70 for engagement about the shank of the bar 16 with clamping means 72 being extended through an intermediate portion of the flat plate for clamping the portion 70 of the bar 16. The remainder of the bracket 68 is arcuated to form a substantially semi-circular means 74. A plurality of resilient clips 76 are secured thereon in a manner similar to the resilient clips on the plate 54. The clips 76 are adapted to receive upper end portions of the shanks of the golf clubs, as seen best in Figure 1 in dotted lines.

The leg means 14 includes a downwardly extending leg 78 which is hingedly connected to the upwardly angulated portion 20 of the handle bar 16 at 80. The bottom end of the leg 78 is adapted to engage the ground at 82 for supporting the carrier when not in use. A resilient spring 84 is connected to the leg 78 and a linkage means at 88 for normally holding the leg 78 in a first position shown in dotted lines in Figure 1. A handle means 90 is reciprocably mounted with respect to the handle bar 16 and has its lower end hingedly connected to the leg 78 at 92. A pair of brackets 94 and 96 are clampingly engaged on the handle bar 16 and are provided with sleeves 98 and 100 for slidably receiving the handle shank 94 of the handle means 90. It will readily be seen that when the golfer desires to leave the carrier in supporting position, the handle means 90 is pulled in opposition to the resilient spring 84 until the leg 78 is in ground engaging position and then the golfer may leave the carrier supporting his golf clubs.

Looking now again at Figures 1 and 3, it will be seen that the plate 54 is securely mounted on the cross bar 22 by means of the pins 53 extending through the apertures 55 in the plate and the apertures 51 in the cross bar 22. With this arrangement, the golf club supporting brackets may be readily removed when it is desired to fold the carrier for storage and the like.

Some changes may be made in the construction and arrangement of the parts of my device

without departing from the spirit and purpose of my invention.

Having described the invention, what is claimed as new is:

5 A folding golf club carrier comprising an elongated handle bar, a pair of wheel supporting bars pivotally connected thereto intermediate its ends and extending towards the forward end thereof, the forward ends of said wheel supporting bars being generally T-shaped and each including a first leg forming an axle and a second leg forming a linkage connecting arm, a connecting bracket extending transversely of the forward end of the handle bar and rigidly connected thereto, linkage extending between and pivotally connected to said second legs of the wheel supporting bars and said connecting bracket whereby said wheel supporting bars may assume a folded and a club carrying relation, wheels rotatably mounted on said axles, a support leg hingedly connected to said handle bar intermediate the forward end thereof and the rear connection of said wheel supporting bars and adapted to engage the ground for supporting the rear of said carrier in an elevated position, resilient means connecting said leg with said connecting bracket for urging said leg to a folded position, linkage carried by said handle bar for moving said leg to a ground engaging position.

GLENN C. WRIGHT.
